METHOD OF MAKING BAGS

Adolph Potdevin, Garden City, N. Y., assignor to
 Potdevin Machine Company, Brooklyn, N. Y.,
 a corporation of New York

Application September 6, 1933, Serial No. 688,279

3 Claims. (CL 93—35)

This invention relates to a method of and apparatus for making bags and to the bag itself as an article of manufacture and is directed to a method and apparatus particularly well adapted for making bags of cellophane, glassine and like materials, as distinguished from paper.

In the accompanying drawing:

Fig. 1 is a plan view somewhat diagrammatic of an apparatus constituting one embodiment of 10 my invention;

Fig. 2 is a side elevation of the apparatus of Fig. 1; and

Figs. 3, 4, and 5 show the bag in the various stages of its manufacture.

Referring to the drawing in detail: The material is taken from a supply roll 1 and the web, designated 2, is led about a roller 3 and past plates 4 which are adapted to fold the opposed edges of the web over toward each other upon 15 the main body of the web to form flanges 5 at opposite sides of the web.

The web then passes between rollers 6 by which the flanges are turned outwardly again so that the web is once more flat.

In its flattened condition the web passes notching mechanism comprising notchers 7 and 8 at each side of the web and adapted to notch the web as shown at 9 and 10. The notchers 7 and 8 are mounted on the same shafts.

The notchers 7 and 8 are held to their supporting shaft 11 by screws 12, so that the spacing of the notches 9 and 10 lengthwise of the web 2 may be varied to suit different conditions.

The web still in opened-up or flat condition 35 then passes about rollers 13 and 14 to bring the flanges 5 of the web into contact with adhesive-applying discs 15.

These adhesive-applying discs as seen from Fig. 2 are segmental so that alternate flanges 5 have 40 the adhesive stripes 16 applied thereto. In other words, the flanges to one side of one pair of opposed notches 9 will have adhesive applied thereto, while the adjacent flanges at the other side of these notches will be left plain.

The discs 15 are made adjustable as shown at 45 17 to vary the length of their periphery.

The web next passes plates 18 which are adapted to turn the flanges 5 which have had adhesive applied thereto inwardly again, so that these 50 flanges will be pasted down to the body of the web 2.

To insure that only alternate flanges will be turned inwardly again, I provide rocking fingers 19 intermediate the roller 14 and plates 18, these fingers which engage the web along the line of

the fold which provides the flanges 5 being so timed that the leading end of a pair of pasted flanges will be directed above the end of the plates 18, while the leading end of the succeeding pair of flanges will be directed below these 5 plates.

The web next passes between rollers 20, past cutting off mechanism 21 and between rollers 22 and 23.

The cutting off mechanism comprises a rotary 10 cutter bar 24 driven in the direction of the arrow on Fig. 1 cooperating with a fixed member 25. The function of this cutting off mechanism is to sever the main body of the web transversely, across opposed notches 10 but an appreciable 15 distance to one side (to the right as viewed in Fig. 1) of the center of these notches so as to leave a relatively long flap designated 26 in Fig. 1 on the trailing edge of the cut off portion and a relatively short flap 27 at the leading edge of 20 the adjacent section of material.

Each length of material, therefore, approximately double the length of the finished bag and as shown in Fig. 1 is composed of what I shall term two panels designated 28 and 29, respectively, the flanges 5 of the panel 28 being turned inwardly over upon the body of the web 2 to which they are pasted, while the flanges 5 on the panel 29 are in an opened up condition.

The length of material shown at the left in 30 Fig. 1 passes from the rollers 23 to forwarding and creasing rollers 30 and 31. The roller 30 is provided with a creaser blade 32 and the roller 31 with a gripper 33 controlled by a cam 34. The setting and timing of these two rollers 30 and 35 31 are such that the creaser blade 32 engages the web substantially along the line 35 of Fig. 1 to force the web downwardly with respect to the roller 31 so that the gripping finger 33 may function to grip the material. Continued rotation 40 of the roller 31 draws the material around with this roller and between the face of the roller and the face of a roller 35 lying adjacent thereto to fold the two panels lengthwise of the web, over upon each other as illustrated in Fig. 3. 45

In this condition the inner faces of the flanges 5 of the panel 29 are contacted with gluing discs 36 which apply adhesive thereto as shown at 37 in Fig. 4.

The folded material then passes between rollers 38 and finally between a pair of superposed belts 39 which fold the flanges 5 of panel 29 over upon the panel 28 as shown in Fig. 5 which completes the bag.

The finished bag, it will be observed, is made

from a single piece of material, its edges being very strongly reinforced by the manner in which the flanges 5 are handled, thus adapting my method for making bags from materials such as cellophane, glassine and like materials which are easily torn.

What I claim is:—

1. The method of making bags which comprises folding the edges of the portion of a bag length 10 which eventually is to constitute one wall of the bag over in superimposed relation to said portion along a longitudinal line adjacent each edge of said portion of the bag length, and pasting the folded over edges to said portion, then folding 15 the bag length along a transverse line which is to constitute the bottom edge of the bag, to bottom the bag and to bring the remainder of the bag length and said wall into parallelism, then folding the edges of the said remainder of the 20 bag length along a longitudinal line adjacent each edge thereof over upon the outer face of said wall and securing the turned over edges to said outer face.

2. The method of making bags which comprises 25 notching the opposed side edges of a traveling web at predetermined intervals, severing the web transversely into bag lengths at alternate notches to provide a bag length with a pair of opposed notches intermediate its ends, folding over the 30 side edges of that part of the bag length which is to one side of said intermediate notches along

a longitudinal line adjacent each edge of said portion of the bag length and pasting the folded-over edges to said portion, then folding the bag length along a transverse line which intersects said intermediate notches, and folding the side 5 edges of the remainder of the bag length along a longitudinal line adjacent each edge thereof over upon the outer face of the bag thus formed and securing the last mentioned folded over faces to said face.

3. The method of making bags which comprises notching the opposed side edges of a traveling web at predetermined intervals, severing the web transversely into bag lengths at the end of alternate notches to provide a bag length with a pair 15 of opposed notches intermediate its ends and a projecting flap on one end, folding over the side edges of that part of the bag length which is to one side of said intermediate notches along a longitudinal line adjacent each edge of said portion of the bag length, pasting the folded-over edges to said portion, then folding the bag length along a transverse line which intersects said intermediate notches and folding the edges of the remainder of the bag length along a longitudinal line adjacent each edge thereof and over 20 upon the outer face of the bag thus formed and securing the last-mentioned folded-over edges to said face.

ADOLPH POTDEVIN. 30
